(57) **CLAIM**

The ornamental design for a cloth for cleaning teeth, as shown and described.

DESCRIPTION

FIG. 1 is a top, front and left side perspective view of the cloth for cleaning teeth showing the new design;

FIG. 2 is a top view thereof;

FIG. 3 is a right side elevational view thereof, the left side being a mirror image;

FIG. 4 is a rear elevational view thereof;

FIG. 5 is a bottom plan view thereof; and,

FIG. 6 is a right side, rear, and bottom perspective view thereof, illustrating a mode of using the present invention.

The surface pattern shown in broken lines on the circular panel of FIG. 1 and the hand in FIG. 5 are for illustrative purposes only and form no part of the claimed invention.
